UNITED STATES PATENT OFFICE.

JESSE A. B. SMITH, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,191,352.

Specification of Letters Patent. Patented July 18, 1916.

Application filed February 10, 1916. Serial No. 77,393.

To all whom it may concern:

Be it known that I, JESSE A. B. SMITH, a citizen of the United States, residing in Brooklyn borough, in the county of Kings, 5 city and State of New York, have invented certain new and useful Improvements in Type-Writing Machines, of which the following is a specification.

This invention relates to means for mounting a number of sheets, such as carbon sheets or sheets of transfer material, to overlie one another, and arranged to be interleaved with sheets or webs, all of which may then be advanced to a platen of a typewriting machine, to be written upon.

The invention is intended more particularly for use in an arrangement as above specified, wherein the series of carbon sheets are shifted from time to time to a fresh 20 portion of the continuous webs with which they are used.

The invention is herein shown as an improvement on that disclosed in the patent to Wernery and Smith, No. 1,132,055, dated 25 March 16, 1915. In said patent there is shown in combination with the usual paper carriage of a typewriting machine, an auxiliary framework extending rearwardly from the carriage, over which may be advanced 30 a series of webs to be fed around the platen; said framework also provides a track on which runs a support or shifter for carbon sheets which are interleaved with the webs, said shifter arranged to advance the carbon 35 sheets with the webs, as the latter are fed over the platen to be written upon, the shifter being movable rearwardly from time to time to bring the carbon sheets opposite fresh portions of the webs. The carbon 40 sheets are mounted on fingers or blades, each connected at one end to said shifter; the blades arranged to project alternately from the opposite ends of the shifter.

An object of the present invention is to 45 provide a simple and practical form of attachment for said shifter to hold additional carbon sheets and thereby increase the carbon sheet-holding capacity of the shifter to any desired extent, and thus permit the use 50 of additional webs up to any desired number within the capacity of the typewriting machine.

The invention provides an attachment which may be placed on existing machines with little or no change in the machines as 55 manufactured.

In practising the invention, I provide at each end of the truck or shifter, a support for carbon sheet-holding blades, each blade mounted at one end on its support and projecting horizontally toward the opposite support, the blades supported at opposite ends of the truck overlapping, and being arranged in alternation; means also being provided to suitably space the blades to permit 60 the webs to pass freely between them. The supports for said blades may each comprise a pair of upright pins removably attached to the truck-frame and projecting upwardly therefrom. Each sheet-holding blade is provided with openings to fit said pins, and thereby hold the blade in a position to extend transversely of the webs, and may also have attached thereto a spacing block for suitably spacing adjacent blades. Each 70 blade may have attached thereto a holding clip pivotally mounted on the blade to swing thereon into and out of sheet-clamping position. Said clips are provided with openings, which when the clip is in clamping position, are in register with the openings in the blade, so as to fit on the supporting pins and thereby lock the clips in sheet-holding 75 position when on said pins. One pin of each pair may project above the other pin 80 to facilitate the mounting of the blades 85 thereon.

Other features and advantages will hereinafter appear.

In the accompanying drawings, Figure 1 90 is a disassembled view of a sheet-carrying blade, its sheet-holding clip and spacing block. Fig. 2 is a fragmentary sectional elevation, showing a number of blades mounted on a pair of supporting pins. Fig. 95 3 is a front perspective view of the carriage of an Underwood typewriting machine with the present invention applied thereto. Fig. 4 is a fragmentary sectional elevation of a pair of supporting pins, and a sheet-holding blade mounted thereon.

A roller platen 10 is mounted on the carriage 11, which may be driven in the usual way, and its letter-feed movement controlled

by the usual mechanism, not shown. Types 12 strike against the front face of the platen to print on the work-sheets or webs fed therewith. An auxiliary frame 13 is connected 5 to the carriage to travel therewith, extends rearwardly from the carriage and provides a web course over which webs may be advanced to a paper shelf 14 at the introductory side of the platen, and thence downwardly and around the platen and upwardly past the printing line.

A shifter or truck 15 is provided with means for supporting carbon sheets or sheets of transfer material, which are interleaved 15 with the webs; said truck mounted on the frame 13 to travel forwardly with the webs, so that the carbon sheets are carried around the platen and alternate with the webs at the printing line for transferring the type 20 impressions to the webs. In order that the carbon sheets may be shifted rearwardly from time to time, to bring them opposite fresh portions of the webs, the platen is mounted on a swinging frame 16 to swing 25 upwardly and release the carbon sheets from the binding action of the platen and its feed rolls.

The truck frame may comprise ends 17 formed with seats 18, arranged in stepped 30 relation to receive the carbon-sheet-holding blades or fingers 19, which project alternately from opposite ends of the frame in position to support carbon sheets, interleaved with the webs.

35 The parts above referred to by reference characters may be the same as the corresponding mechanism disclosed in the patent above referred to, to which reference may be had for a more detailed description.

40 The present invention provides means for increasing the capacity of the shifter 15, or, in other words, for enabling a greater number of carbon sheets to be carried by said shifter. To this end, there are provided 45 pairs of supporting pins 21, 22, which may be removably attached to the frame ends 17, the latter being provided with openings to receive said pins, and in which the pins preferably have a snug fit. Auxiliary blades 50 or fingers 23 for holding carbon sheets 20 in addition to those mounted on the blades 19, are each provided with openings 24, at one end thereof, said openings spaced to receive the supporting pins 21, 22, and so arranged 55 that each blade when in position on a pair of supporting pins, extends inwardly across the frame 13. Each blade has attached thereto or formed thereon a spacing block 25 by which the blade is spaced from the underlying blades. The spacing blocks may be of such thickness that each two adjacent blades mounted on one pair of pins are spaced sufficiently to accommodate a similar blade projecting therebetween, and mounted 60 on the opposite pair of supporting pins, and

also to provide suitable space between the several blades for the passage of the webs of paper. The arrangement of the blades, each supported at one end only, the blades on one pair of pins overlapping and alternating 70 with those on the opposite pins, is adapted to hold carbon sheets interleaved with webs formed of a single sheet or web fan-folded with the folds extending lengthwise thereof as shown in the patent above referred to. 75 The blocks 25 are provided with openings in register with the openings 24 in the blades, so that said blocks may be mounted on the supporting pins. These blocks are of such thickness that they materially aid in supporting the paper-holding fingers or blades in a horizontal position. That is, they counteract any tendency of the blades to tilt on the supporting pins.

The lowermost block 25^a on one pair of 85 supporting pins may be made thinner or of less depth than the remaining blocks, so that the blades supported on one pair of pins are slightly lower than those carried by the other pair of pins, whereby the alternate 90 blades are properly spaced. The spacing blocks 25 may be provided with projections 26 forming finger-pieces, which, when the blocks are on the supporting pins, preferably project at different angles from the several 95 blocks, thereby preventing the projections on one block interfering with the handling of an adjoining block.

A sheet-holding clip 27 may be provided for each blade 23. The holding clip may be 100 in the form of a sheet-metal strip to extend lengthwise of the blade 23 and folded to extend over both the upper and lower surfaces of the blade 23. An end 28 of the clip is pivoted between the blade 23 and its 105 spacing block 25 by means of a stud 29 on said block, said stud projecting through openings 30 and 31 in said blade and clip respectively. The clip is also provided with openings 32, which, when the clip is in sheet-clamping position, are aligned with the corresponding openings in the blade and block, whereby the blade can only be placed on its supporting pins when the clip is in sheet-clamping position, and whereby the clip is 110 locked in said position and positively prevented from becoming displaced while in use. The clip 27 may also be provided with a detent 33 to fit in a corresponding opening 34 provided in the blade 23, and thereby 115 yieldingly hold the clip in sheet-clamping position before it is placed on the supporting pins 21, 22, and also securely hold the carbon sheet on its blade. It will be noted that one of the supporting pins 22 of each pair projects upward a short distance above the other pin, which arrangement materially aids in 120 quickly placing a sheet-holding blade 23 on the pins.

Variations may be resorted to within the 125

scope of the invention, and portions of the improvements may be used without others.

Having thus described my invention, I claim:

5. 1. A device for supporting a plurality of sheets in superposed relation, and spaced to provide for the passage of interleaved sheets or webs, said device comprising a carrying frame, supports at opposite ends of the frame, sheet-carrying blades mounted on each support and projecting horizontally toward the other support, the blades on one support overlapping and alternating with those on the other support, and spacing means separating the blades and providing space between each two adjacent overlapping blades.
2. A device for supporting a series of sheet-holding blades in spaced relation to separate sheets held thereby in superposed relation, and provide space for the passage of interleaved sheets or webs, said device comprising a carrying frame, supports extending upwardly from said frame, a set of sheet-carrying blades removably mounted on each support, the blades on each support projecting toward the other support, with the free ends of one set of blades alternating with and overlapping those of the other set, and spacing blocks arranged to space each two adjacent blades.
3. A device for supporting a series of sheet-holding blades in spaced relation to separate sheets held thereby in superposed relation, and provide space for the passage of interleaved sheets or webs, said device comprising a carrying frame, supports extending upwardly from said frame, a set of sheet-carrying blades removably mounted on each support, the blades on each support projecting toward the other support, with the free ends of one set of blades alternating with and overlapping those of the other set, and spacing blocks carried by said blades, the block on the lowermost blade of one set being of less thickness than the corresponding block of the other set, whereby the blades of one set are elevated with respect to the corresponding blades of the other set to provide space between the overlapping blades.
4. A device for supporting a series of sheet-holding blades in spaced relation to separate sheets held thereby in superposed relation, and provide space for the passage of interleaved sheets or webs, said device comprising a carrying frame, a pair of supporting pins projecting upwardly therefrom, a series of sheet-carrying blades each removably mounted on said supporting pins, and spacing blocks carried by said blades, whereby the blades are held by said pins and blocks in parallel spaced relation to provide space between the sheets supported thereby.
5. A device for supporting a series of sheet-holding blades in spaced relation to separate sheets held thereby in superposed relation, and provide space for the passage of interleaved sheets or webs, said device comprising a carrying frame, a pair of pins carried by and projecting upwardly from said frame, sheet-carrying blades, each provided with openings to receive said pins, whereby the blades are removably supported on said pins to project horizontally therefrom, one over the other, and sheet-holding clips mounted on the blades to swing to and from sheet-clamping position and each provided with an opening to register with one of said openings in the blade when the clip is in sheet-clamping position, whereby the clip is held in said clamping position by one of said pins when the blade is mounted on the pins.
6. A device for supporting a series of sheet-holding blades in spaced relation to separate sheets held thereby in superposed relation, and provide space for the passage of interleaved sheets or webs, said device comprising a carrying frame, a pair of supporting pins projecting upwardly therefrom, and a series of sheet-carrying blades each removably mounted on said supporting pins, one of said pins projecting upwardly beyond the other pin to facilitate the mounting of the blades thereon.
7. A device for supporting a series of sheet-holding blades in spaced relation to separate sheets held thereby in superposed relation, and provide space for the passage of interleaved sheets or webs, said device comprising a carrying frame, a pair of pins carried by and projecting upwardly from said frame, and sheet-carrying blades, each provided with openings to receive said pins, whereby the blades are removably supported on said pins to project horizontally therefrom, one over the other.
8. A device for supporting a series of sheet-holding blades in spaced relation to separate sheets held thereby in superposed relation, and provide space for the passage of interleaved sheets or webs, said device comprising a carrying frame, a pair of supporting pins projecting upwardly therefrom, a series of sheet-carrying units, each comprising a sheet-holding blade, a clip to clamp the sheet to the blade, a spacing block, and a pivot uniting the blade, clip and block, said blade, clip and block provided with openings arranged to be brought in register and to receive said pins.
9. A device for supporting a series of sheet-holding blades in spaced relation to separate sheets held thereby, and provide space for the passage of interleaved sheets or webs, said device comprising a carrying frame, a series of sheet-holding blades, means for attaching said blades to the supporting frame, and means for increasing the

sheet-holding capacity of said frame, said last-mentioned means comprising a pair of holding pins removably attached to said frame and projecting upwardly therefrom, 5 auxiliary sheet-holding blades mounted on said pins, and individually removable therefrom, and spacing blocks carried by said auxiliary blades.

10. In a carbon sheet-holding device, the combination of a supporting frame, pins projecting upwardly from the frame, and sheet-holding blades having openings to receive said pins, the pins and openings being relatively arranged to permit the blades to be lifted off the pins, and to hold the blades parallel when in position on the frame.

11. In a carbon sheet-holding device, the combination of a supporting frame, pins projecting upwardly from the frame, sheet-holding blades having openings to receive said pins, the pins and openings being relatively arranged to permit the blades to be lifted off the pins, and to hold the blades parallel when in position on the frame, and 20 sheet-holding clips pivotally mounted on said blades and each provided with an opening to register with one of said openings in the blade when the clip is in sheet-holding position, whereby each clip is locked in said 25 position when its blade is mounted on said pins.

12. In a carbon sheet-holding device, the combination of a supporting frame, pins projecting upwardly from the frame, sheet-holding blades having openings to receive said pins, the pins and openings being relatively arranged to permit the blades to be lifted off the pins, and to hold the blades parallel when in position on the frame, and 35 spacing blocks attached to said blades, each spacing block provided with openings to register with the openings of the blade, whereby said blocks may be mounted on the pins with said blades.

40. 13. In a carbon sheet-holding device, the combination of a supporting frame, pins projecting upwardly from the frame, sheet-holding blades having openings to receive said pins, the pins and openings being relatively arranged to permit the blades to be lifted off the pins, and to hold the blades parallel when in position on the frame, spacing blocks attached to said blades, each spacing block provided with openings to 45 register with the openings of the blade, whereby said blocks may be mounted on the pins with said blades, and finger-pieces projecting laterally from said blocks to facilitate the placing and removal of the blades.

60. 14. In a sheet-supporting device, the combination with means for supporting and guiding a plurality of superposed webs or work-sheets, as they are fed past the printing line, means for supporting and shifting intervening carbon sheets, said last-mentioned means comprising a shifting frame 105 arranged to be advanced with the webs, blades or arms on which the intervening carbon sheets may be mounted, means for attaching said blades to said shifting frame comprising a pair of supporting pins projecting upwardly from the frame, said blades each provided at one end with a pair of openings arranged to receive said pins, whereby the blades are held, one over another, in parallel relation, and means spacing said blades to thereby separate the carbon sheets and provide space for the interleaved webs.

ing upwardly projecting pins by which the blade is held against rotation on its support, said clip provided with openings to receive said pins when the blade is mounted on the support and thereby lock the clip 70 in sheet-clamping position.

15. Means for supporting a series of sheets, comprising a supporting frame, a series of sheet-holding blades, holding clips pivoted to said blades to swing thereon into 75 and out of position to clamp sheets on said blades, each blade and its holding clip being provided with openings which are in register when the clip is in sheet-holding position, and parallel supporting pins projecting upwardly from said frame, to project through the openings in said blades and clips and thereby hold the blades and prevent rotation thereof on the support and also to lock the 80 clips in sheet-holding position.

16. Means for supporting a series of sheets, comprising a supporting frame, a series of sheet-holding blades, holding clips pivoted to said blades to swing thereon into 85 and out of position to clamp sheets on said blades, each blade and its holding clip being provided with openings which are in register when the clip is in sheet-holding position, parallel supporting pins projecting upwardly from said frame, to project 90 through the openings in said blades and clips and thereby hold the blades and prevent rotation thereof on the support and also to lock the clips in sheet-holding position, said pins being of a length to support a number of blades placed one over another thereon, and spacing blocks carried 95 by the blades.

17. In a typewriting machine, the combination with means for supporting and 105 guiding a plurality of superposed webs or work-sheets, as they are fed past the printing line, means for supporting and shifting intervening carbon sheets, said last-mentioned means comprising a shifting frame 110 arranged to be advanced with the webs, blades or arms on which the intervening carbon sheets may be mounted, means for attaching said blades to said shifting frame comprising a pair of supporting pins projecting upwardly from the frame, said blades each provided at one end with a pair of openings arranged to receive said pins, whereby the blades are held, one over another, in parallel relation, and means spacing 115 said blades to thereby separate the carbon sheets and provide space for the interleaved webs.

18. In a typewriting machine, the combination with means for supporting and 125 guiding a plurality of superposed webs or work-sheets, as they are fed past the printing line, means for supporting and shifting intervening carbon sheets, said means comprising a shifting frame arranged to be ad- 130

vanced with the webs, blades or arms on which the intervening carbon sheets may be mounted, means for attaching said blades to said shifting frame comprising supporting pins arranged in pairs at opposite ends of said shifting frame and projecting upwardly therefrom, said blades each provided adjacent one end with openings arranged to receive the pins of one pair and thereby support the blade in position to extend horizontally toward the other pair of pins, and spacing blocks carried by said blades and arranged to space the blades mounted on one pair of pins, one from another, and also from the blades mounted on the other pair of pins, the blades projecting from one pair

of pins overlapping and alternating with those mounted on the other pair of pins.

19. A sheet-holding unit, comprising in combination, a sheet-holding blade, a clip pivoted thereto to swing into and out of sheet-clamping position, and a spacing block attached to the blade, said blade, clip and block provided with openings arranged to be brought in register to receive supporting pins, the clip being in sheet-clamping position when said openings are in register.
